Primary Examiner — Barbara Fox*Assistant Examiner* — Katie Mroczka*(74) Attorney, Agent, or Firm* — Arent Fox LLP(57) **CLAIM**

The ornamental design for a confection, as shown and described.

DESCRIPTION

FIG. 1 is a perspective view of a confection showing my new design.

FIG. 2 is a front view of the design shown in FIG. 1;

FIG. 3 is a back view of the design shown in FIG. 1;

FIG. 4 is a left side view of the design shown in FIG. 1;

FIG. 5 is a right side view of the design shown in FIG. 1;

FIG. 6 is a top view of the design shown in FIG. 1; and,

FIG. 7 is a bottom view of the design shown in FIG. 1.

The broken lines in the drawings illustrate portions of the confection that form no part of the claimed design.
